BULB MOUNTING

Filed Feb. 25, 1925

Inventor
R. L. Patterson

By *Marvin A. Davis*
Attorney

UNITED STATES PATENT OFFICE.

ROBERT LEE PATTERSON, OF LONG BEACH, CALIFORNIA.

BULB MOUNTING.

Application filed February 25, 1925. Serial No. 11,621.

To all whom it may concern:

Be it known that I, ROBERT LEE PATTERSON, a citizen of the United States, residing at Long Beach, in the county of Los Angeles and State of California, have invented certain new and useful Improvements in a Bulb Mounting, of which the following is a specification.

This invention relates to an improved article of manufacture which may be conveniently designated as a bulb mounting, the same having particular reference to a device of this class which is intended to be used in association with electric light bulbs.

It has been observed that electric light bulbs used in industrial plants and other places are subject to considerable vibration from machinery and within a comparatively short period of time, the rather fragile incandescent filament is broken, thus rendering the bulb useless.

The foregoing circumstances have led me to evolve and produce a novel, yet exceedingly simple and inexpensive device, which I have chosen to refer to as a mounting for such bulbs. The purpose of this mounting is to prevent breakage of the filament by relieving the same of excessive vibration from the cause specified. In other words, the device constitutes a shock absorber.

The particular construction embodied in the improved article will become apparent from the following description and drawing.

In the accompanying drawing forming a part of this application and in which like numerals are employed to designate like parts throughout the same:

Figure 1 is a side elevation of a bulb mounting constructed in accordance with the present invention showing the same in use.

Fig. 2 is a top plan view of the mounting.

Fig. 3 is a perspective view of the same.

In accordance with my idea, a thoroughly resilient member is provided and is interposed between the bulb supporting socket and the wall or other support from which the bulb is to be suspended, the resiliency being such as to reduce shock to a very noticeable degree.

Although the device may be constructed otherwise, it preferably comprises a pair of symmetrical or duplicate segments 1 arranged in spaced relation, or rather in dia-

metrically opposed relation. The ends of these segments are spaced apart, and each segment being provided between its end with a fastener hole 2.

Connected to the bottom faces of the segments 1 and bridging the spaces between the ends of the same are substantially duplicate segments 3 which may be referred to as sectors for the purpose of distinguishing these duplicate parts.

The sectors 3 are likewise provided between their ends with fastener holes 4. The device is molded from a single body of rubber and in top plan it is substantially discular in outline, the same being adapted to conform to substantially in diameter to the diameter of the base 5 of an electric fixture socket 6. In the present instance the socket receives an electric bulb 7 of conventional form.

In use, the segments 1 are placed against a flat supporting surface such as a wall or the like 8, fastening screws 9 being passed through the openings 2 to securely maintain the mounting in place. The base 5 is then placed against the bottoms of the sectors 3 and the retaining bolts 10 carried thereby are passed upwardly through the openings 4. It will be noted that the spaces between the ends of the segments 1 afford sufficient room for permitting application and removal of the nuts on these bolts.

Again, I call attention to the fact that the material of which the improved mounting is made is sufficiently resilient to effectively absorb the shocks to which the filament of the bulb would otherwise be subjected. Yet the quality of the material is also such as to afford a very durable support for the bulb.

In practice the devices vary in shape and size to accommodate fixture supports, and it will be noted that it is immaterial which side of the device is placed against the wall. That is, the segments may bear against the surface of the wall or the device may be inverted and the sectors may be placed against the wall.

These and other advantages and features of the invention have doubtless been made apparent by the foregoing description and drawing. For this reason, a more lengthy description is thought unnecessary.

Although the preferred embodiment of the invention has been shown and described,

it is to be understood that minor changes coming within the field of invention claimed, may be resorted to if desired.

Having thus described my invention, what I claim as new is:

1. As a new article of manufacture, a combined mounting and shock absorber for an electric light bulb socket, comprising a single body of comparatively resilient material shaped to provide attaching portions and portions for connection of the socket, the last named portions bridging the ends of the first named portions to provide spaces between said ends.

2. A device of the class described comprising a body of resilient material including a pair of opposed apertured segments having their ends spaced apart, said segments being disposed in the same horizontal plane, and a pair of sectors underlying said segments and connected to the ends of the latter, said sectors being disposed in a plane with each other and in a plane below the segments to provide spaces between the ends of the latter.

In testimony whereof I affix my signature.

ROBERT LEE PATTERSON.
